Primary Examiner — L. A. Grabenstetter

Assistant Examiner — Danielle Nichole Bowly

(57) **CLAIM**

The ornamental design for a binder with zip, as shown and described.

DESCRIPTION

FIG. 1 is a front, right and top perspective view of a binder with zip, showing my new design.

FIG. 2 is a front, right and top perspective view of the binder with zip, shown in an environment of use.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines showing stitching in the figures form no part of the claimed design; the additional broken lines for the shoulder straps shown in FIG. 2 are for purposes of illustrating environmental subject matter only and form no part thereof.

1 Claim, 8 Drawing Sheets
